[57] CLAIM

The ornamental design of a recessed wall mounted lighting fixture, as shown and described.

DESCRIPTION

FIG. 1 is a perspective view taken from one side of the recessed wall mounted lighting fixture of the invention mounted in a recessed configuration in a wall and having a diffuser structure which is unpatterned;

FIG. 2 is a front elevational view of the lighting fixture of FIG. 1;

FIG. 3 is a perspective view taken from one side of a second embodiment of the lighting fixture of the invention which has a diffuser structure with a pattern of slots formed therein; FIG. 4 is a perspective view taken from one side of a third embodiment of the lighting fixture of the invention which has a diffuser structure with a pattern of circular apertures formed therein;

FIG. 5 is a perspective view taken from one side of the lighting fixture of the invention having a diffuser structure with a pattern of circular apertures formed therein;

FIG. 6 is a front elevational view of the lighting fixture of FIG. 5.

FIG. 7 is an enlarged fragmentary view of the slot pattern shown on the diffuser in FIGS. 3 and 4, the lighting fixture being fragmentarily shown for convenience of illustration; and

FIG. 8 is an enlarged fragmentary view of the hole pattern shown on the diffuser in FIGS. 6 and 7, the lighting fixture being fragmentarily shown for convenience of illustration. The broken lines are shown for illustrative purposes only and form no part of the claimed design.
